CANOPY

Carl X. Meyer, St. Louis County, Mo., assignor, by mesne assignments, to The Emerson Electric Manufacturing Company, St. Louis, Mo., a corporation of Missouri

Filed July 11, 1962, Ser. No. 70,879

Term of patent 14 years

(Cl. D48—7)

FIG. 1

FIG. 2

FIG. 1 is a perspective view as seen from below of a canopy showing my design;

FIG. 2 is a side elevational view thereof, the opposite side that is not shown being substantially the same;

FIG. 3 is a bottom plan view thereof; and

FIG. 4 is a transverse sectional view taken at line 4—4 in FIG. 3.

I claim:

The ornamental design for a canopy, substantially as shown and described.
